UNITED STATES PATENT OFFICE.

ALBERT A. CARPER, OF BALTIMORE, MARYLAND, ASSIGNOR TO THE ALUMINUM STOPPER COMPANY OF BALTIMORE CITY, OF MARYLAND.

MACHINE FOR SEALING BOTTLES.

SPECIFICATION forming part of Letters Patent No. 623,274, dated April 18, 1899.

Application filed December 13, 1897. Serial No. 661,634. (No model.)

To all whom it may concern:

Be it known that I, ALBERT A. CARPER, of the city of Baltimore, in the State of Maryland, have invented certain Improvements in 5 Machines for Sealing Bottles, of which the following is a specification.

This invention relates to a machine especially adapted to expand within the throat of a suitably-constructed bottle the improved 10 hollow metallic plug shown and described in Letters Patent No. 541,203, granted on the 18th day of June, 1895, to Robert A. Hall.

In the description of the said invention which follows reference is made to the accompanying drawings, forming a part hereof, and in which—

Figure 1 is a partly-sectional side view of the improved bottle-sealing machine, with the upper parts thereof removed, together 20 with a bottle which is shown in the position which it occupies before the insertion in the throat thereof of the hollow metallic plug before referred to. Fig. 2 is a central vertical section of the parts omitted in Fig. 1. Fig. 25 3 is an enlarged central section of the lower part of the sealing-head, together with the head of a bottle, illustrating the relative positions of the various parts before the inserted hollow plug is expanded to form a tight joint. Fig. 4 is a view similar to Fig. 3, except that 30 the plug-expanding devices are shown in the positions which they relatively occupy after the sealing operation. Fig. 5 is an under side view of the sealing-head. Fig. 6 is an under 35 side view of the seal-expanding device alone on a still enlarged scale. Fig. 7 is a cross-section of Fig. 6 on the dotted line $x-x$. Fig. 8 is a central vertical section of a sealed bottle-head on the same scale as Figs. 6 and 7.

Referring now to the drawings, A is a hollow columnar stand having three legs a secured thereto by bolts, as shown in Fig. 1.

B is the head of the columnar stand, consisting of a laterally-extending box provided 45 with a boss b , which is bored to receive the turned end of the column. The head is secured in place by means of a bolt (not shown) inserted through the hole c , whereby the portion of the box which surrounds the column 50 and is slotted is constricted upon the column.

C is the sealing-head, consisting of a shell e , the bore of which is cylindrical and the outside slightly conical. It is slotted longitudinally from the lower end to the point Z , and thereby divided into a number of spring- 55 segments of uniform width. In the drawings the slotted portion of the shell is shown as divided into eight segments, but the number may be increased or diminished without materially affecting the invention. The upper 60 end of this shell is screwed into the overhanging portion of the head B of the columnar stand A and in contact with an annular projection f . (See Fig. 2.) The lower end of the slotted shell is provided with an annular flaring lip 65 h , which terminates within the shell in a flat annular face i .

To equalize outward movement of the segments of the shell, imparted to them by forcing an object into the mouth, and also to increase the inherent stiffness of the segments, I form an annular groove in the shell immediately above the outer edge of the lip and insert therein a spring j , preferably consisting of a wire spiral with its ends connected 70 to form a ring. By means of this reinforcing-spring a uniform expansion of the lower end of the hollow plug-expanding head is obtained when the head of a bottle is forced into its mouth. 75

The segments of the shell are provided with plate-springs g , which extend from the outer edge of the lip h to the mouth and serve to center the bottle-head before its outer surface can effect any movement of the segments. 80 These subsidiary springs are not absolutely essential, but they have the effect of making the inner surface of the segments elastic and yielding. 85

The expander or device which directly sets 90 out the hollow metallic plug E as an entirety is denoted by D, and it consists of a disk in segments m . (Shown particularly in Figs. 6 and 7.) When the segments are closely in contact, as shown in Figs. 3, 6, and 7, its upper surface is flat and the diameter of the disk corresponds with that of the bore of the shell, and its under face presents a button of a depth equal to that of the hollow metallic plug, having a flaring edge and a countersunk 95 100

lower face *q*. The disk is also provided with a peripheral bead *o*. By this construction of the disk each segment *m* has an outwardly-projecting finger *r*.

5 The expander is placed in the shell *e*, with its peripheral bead *o* resting on the flat face *i* of the lip *h*, before referred to, and when so supported the segments of the disk may be tilted and made to assume the positions shown 10 in Fig. 4 by pressing the center of the disk.

II is a spindle extending from the upper face of the expander *D* into the hollow head *B* of the columnar stand *A*, where it is provided with a head *s*. The lower end of the spindle 15 is threaded and fitted with a flanged nut *t*, and between the flange of this nut and the flange of a sleeve *u*, which bears against the under side of the head *s*, is coiled spring *F*.

To prevent buckling of the coiled spring *F* 20 in its compression by means of the nut *t*, an unsupported loosely-fitting sleeve *G* is placed on the spindle, as shown in Fig. 2. The length of this sleeve is such that it will not come in contact with both the nut *t* and the sleeve *u* 25 when the coiled spring is fully compressed.

Over the head *s* of the spindle *H* and in contact with the flange of the sleeve *u* is a hollow cap *I*, having a rounded end and a flange, which is confined between the sleeve and the 30 projection *f* in the head *B*. This cap is of such depth as to admit of a limited upward movement of the head *s* when the spring *F* is compressed beyond the compression shown in the drawings by lifting the spindle.

35 The spindle *H*, with its attachments, as described, is supported by the expander *D*, the yielding shell *e* resisting the tendency of the segments of the expander to assume the tilted position shown in Fig. 4 until some force is 40 applied to the upper end of the spindle.

J is a recessed circular table for the bottles to be sealed, fastened to the end of a stem *K*, which is adjusted endwise within a spindle *L*, adapted to slide in the brackets *M* and *N*, extending from the columnar stand *A*.

45 *O* is a set-screw for holding the stem *K* after its adjustment with reference to the spindle *L* to suit the length of the bottles to be sealed.

50 A bottle (denoted by *X*) is shown in Fig. 1 as seated on the table *J*.

P is a cross-lever fulcrumed at *a'* to the columnar stand *A*. Its outer end is forked and fits the spindle *L*, which is cut away at the sides to produce the curved faces *b'* above and below the lever, with which the similarly-curved surfaces of the lever come in contact. The inner end of the cross-lever *P*, within the columnar stand *A*, is connected by the extensible link *R* to a treadle *Q*, pivoted at *c'* to the back leg *a* of the stand *A*. This link is formed of the threaded eyes *d'* and *e'*, the former being attached to the cross-lever *P* and the latter to the treadle and the coiled spring *f'*, the ends of which are screwed onto the threaded portion of the eyes.

55 *S* is a lever situated in the hollow head *B*

and fulcrumed therein at *g'*. Its free end has a slot *h'* to receive the pin *i'* at the upper end of a rod *T*. The rod *T* extends down 70 through the columnar stand *A* to the treadle *Q*, to which it is united by a pin *k'*.

U is an adjustable stop for the lever *S*. It consists merely of a bolt and a locking-nut.

The operation of sealing bottles by means 75 of my improved machine is as follows: The first operation consists in placing an unexpanded hollow metallic plug over the button of the expander, which it fits tightly. A filled bottle is then placed on the recessed 80 table *J*, and the operator presses the treadle *Q* with his foot. In the first part of the downward movement of the treadle the pin *i'* is lowered in the slot *h'* of the lever *S*, and the said lever consequently falls of its own gravity 85 until it comes in contact with the top of the cap *I*, which forms the upper termination of the stem *H*. During and by this operation the bottle is raised until its head enters the flaring mouth of the sealing-head, and its 90 extreme end is brought in contact with the flat face around the button of the expander *D*. On entering the sealing-head the bottle receives the hollow plug, which, it will be remembered, is held by the button of the expander. 95 As the depression of the treadle continues the lever *S* is drawn down by the pin *i'* and the stem *H* thereby forced down by the cap *I* through the medium of the yielding spring *F*, coiled about it. The bottle now 100 being stationary, the lower end of the stem 105 tilts the segments of the expander, as shown in Fig. 4, and their fingers are thereby set out and circumferentially expand the hollow plug.

The object of the stop *U* is to limit the downward motion of the lever *S*, and consequently the spring-pressure of the stem *H* on the expander. The danger of breaking the bottles 110 is thereby reduced.

115 While the movement of the treadle has been described as consisting of two steps, in practice the operation is a single and continuous one, the steps being merely described to illustrate the action of the machine and the nature of the invention.

120 The reason for employing an extensible instead of a rigid link or connection between the lever *P* and the treadle is that the movement of the lever *S* has to be continued after the lever *P* comes to rest. Otherwise the bottle-head would lift the expander.

125 To adapt the apparatus to properly expand the hollow plug without placing undue strain on the bottle, a seal is placed on the button of the expander and the stop *U* adjusted so that the extreme downward movement of the lever *S* will expand the seal to a diameter slightly greater than that of the throat of the bottle.

130 In the operation of the machine the extra movement of the lever *S* or that in excess of what is required to set out the hollow plug tightly against the inner surface of the throat

of the bottle is taken up by the spring F, the stem H being practically shortened in the compression of the said spring.

I claim as my invention—

5. 1. In a machine for expanding a hollow plug in the throat of a bottle, an expander consisting of a disk having a button on its underside adapted to enter the hollow plug to be expanded, the said disk and button being in segments substantially as described, combined with means to press on the upper surface of the said disk and thereby tilt the segments thereof, substantially as specified. 55
10. 2. In a machine for expanding a hollow plug in the throat of a bottle, an expander which consists of a disk having a button on its under side adapted to enter the seal to be expanded, and also a downwardly-extending annular lip, the said disk being in segments substantially as described, combined with means to support the annular lip of the disk, and mechanism to depress the center of the disk and thereby tilt the segments and expand the button in the hollow plug substantially as specified. 60
15. 3. In a machine for expanding a hollow metallic plug in the throat of a bottle, the combination of a hollow sealing-head which is expansible at its lower end, an expander in segments having an expansible button on its under side, supported in the said head, and mechanism to depress the central portion of the said expander, and thereby tilt the segments thereof within a hollow metallic plug placed over the button, substantially as specified. 65
20. 4. In a machine for sealing bottles, the sealing-head thereof, or the lower portion of the same, slotted to form flexible segments combined with an expansible device to distend a plug which is held in a contracted condition by means of the segments of the head, and means to distend the expander against the yielding segments of the head, substantially as, and for the purpose specified. 70
25. 5. In a machine for sealing bottles, the sealing-head thereof made expansible at its lower end by slitting it into segments, combined with reinforcing-spring which is applied to the outside of the expansible portion of the head, substantially as specified. 75
30. 6. In a machine for expanding a hollow metallic plug in the throat of a bottle, the combination of a sealing-head having a flared mouth to receive the head of the bottle, an expander situated in the said head, a compressible stem to operate the said expander, a lever placed over the upper end of the stem having a slot at its free end, a treadle, a link which unites the treadle to the slotted lever in such manner that the treadle may be forced down for a certain distance without communicating movement to the said lever, a vertically-moving table on which bottles to be sealed are placed, a lever to operate the said table, and an extensible link to connect the said lever with the treadle, substantially as specified. 80
35. 7. In combination with a sealing-head having a flaring mouth, and made expansible by slitting it into segments as described, plate-springs which are attached to the outer lip of the mouth of the head and extended within the mouth, substantially as, and for the purpose specified. 85
40. 8. In a machine for expanding a hollow metallic plug in the throat of a bottle, the combination of a sealing-head having a flared mouth to receive the head of the bottle, an expander situated in the said head, a compressible stem to operate the said expander, a lever placed over the upper end of the compressible stem, a treadle, a link which unites the treadle with the lever, the connection being such that the treadle may be forced down for a certain distance without communicating movement to the said lever, a vertically-moving table on which bottles to be sealed are placed, a lever to operate the said table, and an extensible link to connect the said lever with the said treadle, substantially as specified. 90
45. 9. In combination with a sealing-head having an expansible flaring mouth, plate-springs which extend from the exterior to the interior of the said mouth to form a resilient centering device for the heads of the bottles, substantially as specified. 95
50. 10. In combination with a sealing-head having an expansible flaring mouth, plate-springs which are attached to the lip which surrounds the mouth and enters the said mouth to form a resilient centering device for the heads of bottles, substantially as specified. 100

ALBERT A. CARPER.
